CLAIM

The ornamental design for a transparent package for an inflatable pillow, as shown and described.

DESCRIPTION

FIG. 1 is an isometric view of a transparent package for an inflatable pillow showing my new design;

FIG. 2 is a front elevational view thereof;

FIG. 3 is a top end view thereof;

FIG. 4 is a left side elevational view thereof, the undisclosed opposite side being a mirror image;

FIG. 5 is a rear elevational view thereof; and,

FIG. 6 is a bottom end view thereof.

The broken line showing of a bath pillow is for illustrative purposes only and forms no part of the claimed design.
